VENDING MACHINE

Charles J. Warren, Cincinnati, Ohio

Application October 13, 1941, Serial No. 414,795

8 Claims. (Cl. 225—21)

My invention relates to coin-controlled dispensing or vending apparatus, and more especially to apparatus of that character for dispensing, under coin control, liquids, as for instance, orange juice or other fruit juices, milk, ginger ale and like beverages, or any other liquids which it may be desired to dispense.

An object of my invention is to place a cup and to dispense a certain quantity of liquid into the cup, by simple operation with the supply of a coin as a prerequisite to the operation.

A further object is to supply a cup to the position for receiving the liquid, in which position the cup is accessible for manual removal, incident to each dispensing operation.

A further object is to keep the liquid cool for preservation of the liquid and to make it more palatable.

Further and more particular objects are to guard against tampering with the mechanism or clogging of the means for liquid discharge; to insure that a cup is filled with the quantity dispensed before it can be taken by the customer; to guard against injury of persons tampering with the machine; and to provide as fully as possible for sanitation at the place of delivering the filled cup. A further object is to enable several customers to receive cups of liquid in rapid succession, as many as are initially provided for delivery by deposit of a like number of coins. In general, the object is to have the machine as a whole of attractive and inviting appearance, sanitary, self-contained and retentive of waste material, and making the machine suited for use in places where neatness of appearance of the machine and its surroundings is essential.

Other objects will appear in the course of the following description, illustrated by the accompanying drawings, in which—

Figure 1 is a front elevation of a machine embodying my invention, illustrating the exterior appearance;

Fig. 2 is a horizontal cross section of the same on the plane of the line 2—2 of Fig. 1;

Fig. 3 is a vertical-sectional front elevation of the same on a somewhat enlarged scale, the door of the cabinet being removed, and the section being on the plane of the line 3—3 of Fig. 2;

Fig. 4 is a partial horizontal cross section similar to that of Fig. 2, the delivery casing being in horizontal cross section on planes of the broken line 4—4 of Fig. 3, the portion shown being the forward left assembly of the upper part of the machine, and being on a scale considerably enlarged over those of the preceding views;

Fig. 5 is a schematic perspective view of the operating mechanism to make clear the timing of the operations of various parts;

Fig. 6 is a diagram further to illustrate the timing;

Fig. 7 is a front elevation corresponding to that of Fig. 3, but being on the enlarged scale of and showing the details shown in Fig. 4;

Fig. 8 is a front elevation, further enlarged, of the cup-delivery device, with a front plate removed to reveal details of the interior mechanism;

Fig. 9 is a partial front-to-rear vertical section on the plane of the line 9—9 of Fig. 4, on the same scale as that of Figs. 4 and 7, cups in various positions being illustrated by dash lines;

Fig. 10 is a schematic perspective view illustrating the electrical and other details of the coin control and means for successive deliveries in accordance with pre-deposited coins.

In the example disclosed, a cabinet has a base 1, back wall 2 and side walls 3, and has a front with a door 4 on hinges 5 at the left; this door extending from base 1 to the top of the cabinet, which is closed by a cover 6 having hinges 7 on the top edge of cabinet back wall 2, and having a lock 8 at the front, on door 4; the upper edge part of door 4 being held within the cover 6 when the latter is closed down, so that lock 8 locks both cover and door in closed positions. About midway of the height of the cabinet is a shelf, which comprises two sections. The left section 9 is detachably held in the cabinet and its right edge part overlaps the left edge part of right section 10, which extends about half-way across the cabinet and is permanently secured to right wall 3 and back wall 2, and by a brace 11 to the cabinet front just inside the door opening thereof.

The left shelf section 9 has, at its left edge, an upstanding plate part 12 which lies up along the left cabinet wall 3 and is hung thereon tightly by means of stirrups 13 on wall 3 through slots in plate part 12. Both shelf sections 9 and 10 have front turned-down flanges 9' and 10'; the before mentioned brace 11 being fixed to right section flange 10', and left section flange 9' having a socket 9'' on its inner side tightly receiving the upper end of a like brace 14 fixed to the cabinet front at the left side of and just within the door opening. Removable left shelf section 9 thus is supported by the left wall stirrups 13, the fixed right shelf section 10 and the left brace 14. The fixed right shelf section 10 has on it the raised platform 15 supported by the right side wall 3,

back wall 2, and a leg 16 at the front edge of the platform, fixed to shelf section 10.

This platform 15 supports the liquid container and its cooling coils, which are connected to the compressor which with its assembly is mounted on cabinet base 1 in the lower cabinet compartment. The removable shelf section 9 supports the operating mechanism, which is removable thereon. This is of advantage, both in factory assembly of the mechanism, and in repair or adjustment of the mechanism, in servicing the machine. The coin-receiving device 17 is mounted on the right hand side of the cabinet front, just within the door jamb; and being obtainable on the market, and per se not being of my invention, needs no more detailed description than that it is so designed that the passage of a coin down to box 17' will establish an electrical connection between two otherwise disconnected conductors. The device 18 to provide for successive operations corresponding to the number of coins passing down through receiving device 17 is mounted on the left cabinet wall 3 just above the upright plate part 12; and also being obtainable on the market, needs no detailed description further than later will be given in reference to Fig. 10.

The compressor assembly before mentioned comprises the compressor 19, a small electric motor 20 which drives it, with a cooling fan 21 on the motor shaft, and a radiator 22 at the rear, next to a meshed screen part 22' of cabinet back wall 2, which admits air which the fan 21 drives against the return coils 23 leading into compressor 19, and the compressed-refrigerant coils 24 leading from the compressor. These coils 23 and 24 extend as tubes 23' and 24' up through an opening 24" in shelf section 10, to connect to respective ends of the coils 25 around inner tank 26 within outer casing 27 on platform 15. Tank 26 opens through the top of casing 27, with a gasket 28 on which rest the shoulders of an inverted bottle 29. The parts are understood to be so arranged that liquid in tank 26 is kept at a substantially constant height by out-flows from bottle 29 as quantities are drawn from the tank. A stirrer 30 comprising a central hub and opposite blades 30' has its hub fixed on a shaft 31, in the bottom part of tank 26; the shaft extending through the bottom of the tank with a stuffing box 32 around it. The lower end of shaft 31 is connected to the shaft of a small motor 33 fixed on the shelf section 10. Up to the left on the back wall 2 of the cabinet, is a thermostat 34, connected by small tube 34' to coils 25; this thermostat being suitably connected with compressor motor 20, to start and stop the motor as temperature rises and falls, as is well known in the art of electric refrigeration. The small stirrer motor 33 may operate with the cooling device to prevent settling, as of pulp in fruit juice, and to keep the liquid moving for better exposure to cooling.

A small electric lamp 35 is mounted on top of the thermostat 34 to illuminate the interior of the cabinet when the mechanism is being serviced, and when the large bottle 29 is being removed, filled and replaced. The motor 36 which drives the operating mechanism, together with this mechanism, is mounted on a shelf 37 fixed to the upstanding plate part 12; therefore being removable with shelf section 9 and with the mechanism as before mentioned. The electrical connections for the motor 36 as well as other parts are made at a group of sockets 38 receiving plugs 75

of the several connections detachably. The plate 17' with a slot where the coin is inserted is on the outside of the right door jamb part of the cabinet front; and below this is a cup 39 understood to receive coins rejected by the coin device 17 in a manner well known in such a device. In the door 4 is an aperture, below the plane of the cabinet shelf sections 9 and 10, being closed by a shutter 40 hinged at the top of the aperture to close by gravity; and in the lower cabinet compartment, above the refrigerating assembly before described, is a removable bin 41, on brackets 41'. shown in Fig. 3. Used cups are inserted through the aperture by pushing open shutter 40, to drop into bin 41. On the upper part of door 4 is a plate 42, which may be a mirror as represented; or it may be transparent glass for shining of light from lamp 35 inside the cabinet. A frame 43 fits in an aperture in the door 20 to have its bottom slightly above the plane of the top of cabinet shelf sections 9 and 10; this frame bounding the opening through which the filled cups are taken from the machine.

The liquid is delivered from the tank 26 to the 25 cups through the faucet 44 connecting by elbow 44' through the bottom of tank 26 and passing through outer casing 27. This is a faucet of well known design, with the plug 45 turned about 90 degrees from its closed position shown in the 30 drawings, to its open position alining the plug port 45' with the faucet passage which latter ends with a down-turned spout 46. The top of the faucet plug 45 has the upwardly and laterally curved arm 47 ending with a hub 47' having a vertical passage through it. A pin 48" in the plug bears on the top rim of the faucet body to limit the tightness with which the tapered plug 45 may be held in the faucet body by pressure of the spring 48 around the plug stem 49 above a nut 49' and washer 49" on the stem. Ordinarily, a simple washer would be interposed between the top of the spring 48 and the bottom rim of the faucet body; but here, a washer in the shape of a cam 50 is so placed, and the stem 49 is made square at 50' to fit a square hole in cam 50, so that cam 50 turns with the faucet plug 45. The shape of this cam 50 is best seen in Fig. 4, where it is seen to have a peripheral portion 51 of least radius for about 120 degrees, succeeded in both directions by abruptly starting portions 52 and 53 of larger radii, around to a nose 54 of considerably greater radial extent than portions 52 and 53, and rather abruptly starting from these portions at its respective sides. Looking down at the cam, this nose 54 is displaced clockwise about half its width from the plane of the radial line of the faucet plug arm 47; and it is about diametrically opposite a median radial line of the least-radius part 51. The delivery casing 55 is hood-shaped with closed back and open front, with rounded top; the sides, bottom and top of the casing having their front edges coinciding with the back edges of the frame 43 in the door aperture, and the 65 edges of the two members coming close together when the door is closed, so that casing 55 and frame 43 in effect form one structure. The frame 43 flares somewhat forwardly; the bottom 56 of the casing is substantially plane; and the 70 sides and top of the casing curve convergingly backward so that the rear casing wall is narrower and of less height than the open front. This rear wall has a rectangular aperture 57 of ample width and height for passage of a cup therethrough as best seen in Fig. 7 where a cup

K is represented in dash lines. Standing up from the plane bottom 56 is a pair of guide ribs 58 from front to rear and spaced laterally sufficiently to easily take the bottom of the cup K between them. Hollow bosses 59 and 60 extend out laterally from the respective ribs 58, each opening into the space between the ribs. The plane bottom 56 has perforations 61 through which liquid spilled may drain into a pan-shaped base 62 on which the casing 55 is fixed by four screws 63.

Two of these screws 63 are at the front, and both the casing 55 and the base 62 have rear extensions near the rear ends of which the other two screws are located. Guide bars 64 are interposed at opposite sides between casing 55 and base 62 with rabbets in their upper corners, in which the cup carrier 65, a rectangular plate, has its lateral edges guided. The four screws 63, passing through bars 64, hold the casing, bars and base in assembly. Short rear ribs 66 extend back from the sides of aperture 57 in alignment with front ribs 58, and flare rearwardly; and the casing bottom 56 ends, between these rear ribs 66 with a downwardly backwardly inclined portion 67. The carrier 65 slides closely under this rear end portion 67 and the main part of casing bottom 56, being, however, down from bottom 56, leaving space 68 for drainage from perforations 61. A tension spring 69 hooks to the rear end of carrier 65 and to cabinet back wall 2.

The pusher 70 is an upstanding slightly rearwardly inclined plate concave transversely on its front face, and having at its top corners backwardly bent guide ears 71, and having unitary with its lower end a rear extension 72 with its rear end part 72' set down and fixed to the rear end part of carrier 65, supporting pusher 70 to pass along the top of the casing bottom portions 67 and 56 in its forward travel with the carrier 65. Pusher 70 widens from its bottom upward; being narrow enough at its bottom to pass between casing bottom guide ribs 58, and its top being wide enough to extend sufficiently around the wider upper part of cup K which finds space of sufficient dimension, front to rear, between pusher 70 and the casing back wall, to rest down in front of pusher 70 when the carrier 65 is in its rearmost position, as shown. A stud 73 is fixed in the carrier 65 on its bottom, about under the pusher 70, and projects downward from the carrier. To admit operating means to this stud, the left wall of base 62 has a long notch 62' in its upper edge. The base rear extension bottom has down through it an opening 74 registering with an opening 74' in the shelf section 9, to drain from the base down into the cup bin 41.

The screws 63 before mentioned, threaded down through base 62 to hold together the base, the guide bars 64 and the delivery casing 55, project below to go through holes in the shelf section 9, receiving nuts 63' therebelow to attach the assembly firmly to the shelf. The base pan ordinarily may be cleaned by flushing through the casing bottom perforations 61; and for occasional thorough cleaning of the pan, as of fruit pulp or the like sticking to it, the assembly is easily removed and taken apart. The drainage does not usually rise to the bottom of the pan wall notch 62'.

Properly located a considerable distance to the left from the delivery assembly, a boss is unitary with shelf section 9, with an upstanding stud 75. A lever with a long arm 76 extending to the

right and a short arm 77 extending forward from a hub 78 has this hub around stud 75, held down thereon by pin 75' through the stud. Each arm ends in a fork; the fork of the longer arm 76 straddling the depending stud 73 of the carrier 65. The notch 62' in the pan wall makes space for swinging of this arm to move the carrier forward and backward.

At the bottom of the aperture 57 of the delivery casing back wall, the casing base is transversely slotted, and a gate-guide bar 79 extends to the right with its upper front corner rabbeted and continuous with the slotting of the base. At the top of aperture 57 the upper gate-guide bar 80 extends from the left corner of the aperture to the right, with its lower front corner rabbeted. Both bars 79 and 80 extend somewhat past the right hand side of the casing 55 and are secured to the casing by screws 79' and 80', respectively. The gate 81 is a rectangular plate with its lower and upper edges slidably fitting, respectively, in the base slot and lower bar rabbet, and in the upper bar rabbet, and against the flat rear surface of casing 55. It is of ample length along the guides to avoid binding; and when it is across the aperture its left end part, curved backward, wedges to the rear edge of an upright rib 82 that forms the left side of the aperture and has its rear side inclining to the left backwardly from a front edge 82' that is spaced forwardly from gate 81 to form a guard against persons getting their fingers into the place of wedging. Near its right end, gate 81 has fixed to it a bracket 83, extending backward and downward with a lower end part gripping a rod 84 that has its end just to the right of bracket 83 hook shaped. The tension spring 85 connects to this hook shaped end and to the right cabinet wall 3, tending to pull gate 81 open to the right. The rod 84 extends to the left through rear bottom extensions 67, over carrier plate 65, to near the left cabinet wall 3.

The rear of the top of delivery casing 55 is formed with a rearwardly opening bay with a floor 86 just above casing rear aperture 57, and has walls 87 diverging backwardly from the mid-width of its front; and walls 87 have continuation below floor 86 to form a depending guard flange 86'. Just back of the forwardmost part of the walls and flange, floor 86 has down through it the opening 88, through which depends the faucet spout part 46.

The operating parts are so designed, as later will be described, that carrier 65 and its pusher 70 stop forward sliding at a point where cup K slid by pusher 70 forward on casing bottom 56 is stopped with its center about under the center of spout portion 46. The ribs 58 of casing bottom 55, as well as the forward concavity of pusher 70, keep the cup in its correct path of forward travel. The hollow bosses 59 and 60 that extend from the ribs 58 as before mentioned are so located as to be on a left-to-right line through the center of the cup K when it has been placed under spout portion 46 by operation of carrier 65 and pusher 70 as has just been described, to receive liquid. In left boss 59 is gripper 89, being a wire that extends its right end from the boss and bends down through a hole in the bottom of the hollow boss interior to end in a horizontal left end part 90 extending through a depending lug 91 on the under side of the casing bottom 56. A clamp screw 92 threaded down through bottom 56 and lug 91, clamps against the side of gripper part 90 when screwed entirely down; the

head of the screw being countersunk in the upper surface of the casing bottom. This permits adjustment for the gripper to project more or less into the cup space between the casing bottom guide ribs 58. In the right boss 60 is a gripper 93, similarly formed but having its right hand part 93' long, to project through a notch in the pan base wall, somewhat past which the wire is bent backward as an arm 94, then upward alongside the casing 55 as a shaft 95, and then backward as an upper arm 96. Bearings 97 and 98, fixed to casing 55, embrace shaft part 95 next to the lower and upper bends, respectively, limiting upward and downward slippage of the formation. A flat spring 99 is fixed on the pan base side and extends back, bearing on the gripper formation at the bend joining lower arm part 94 with gripper 93, where it has an aperture so that it embraces gripper right end part 93'; thus yieldingly holding the gripper so that its left end is drawn into the boss 60 from the space between guide ribs 58. It will be understood that gripper 93 fits loosely in boss 60, and the wire of which it is made can bend slightly, giving the effect of a pivotal connection between part 93' and arm part 94.

With gripper 93 thus drawn in, upper arm part 95 bears on faucet-plug cam 50 at the abrupt starting of cam peripheral portion 52 with the faucet closed by having plug port 45' at right angles to the faucet passage, as seen in Fig. 4, where turning the plug counter-clockwise will align port 45' with the passage for discharge of liquid from tank 26. When the cam 50 turns with the plug in this direction, upper gripper arm part 96 rides out onto cam part 52, so that gripper 93 is projected into the space between the guide ribs 58. A cup K located under the spout 46 as before explained thus will be gripped between gripper 93 and gripper 89; these slightly indenting the paper cup walls down, very close to the cup bottom; firmly holding the cup against removal while the faucet is open, yet not impairing the cup walls, as the grippers are blunt at their gripping ends. As the faucet is closed, arm part 96 rides off of cam part 52, allowing spring 99 to draw the gripper 93 into boss 60 again, so that the filled cup may be removed. On the floor 86 of the delivery casing rear bay, a boss journals a short vertical shaft 100 extending below and above floor 86 and therebelow having fixed on it a guard wing 101, and thereabove having fixed on it a dog 102 with a nose bearing on the periphery of faucet-plug cam 50. These parts are so relatively positioned on shaft 100 that when the dog nose is at the verge of the rear side of cam nose 54 the wing 101 has its radially outer end part under spout 46, preventing access to the interior of the spout when the faucet is closed. Quickly, in beginning opening of the faucet, the nose of dog 102 rides down the rear side of cam nose 54 because of action of a compression spring 103 between the left side of the dog 102 and a lug 104 on the left rear part of the floor 86; so that the wing 101 is swung backward from under spout 46 before plug port 45' reaches the faucet passage to allow liquid to start flowing through the spout 46. As the faucet is closed, the dog nose rides out onto cam nose 54, swinging wing 101 under spout 46.

Over the space between the backwardly positioned cup pusher 70 and the gated back of casing 55 is the cup-supply device comprising a casing 105 of rectangular shape, fixed on a bracket 106 that extends to the right from shelf 37 before

mentioned as supporting the operating mechanism. This cup casing 105 has centrally down through it the vertical chute 107 for the cups, of circular cross section very slightly greater in diameter than the outer diameter of the rims k of the cups. An extension 108 lengthens the chute downwardly, in an aperture in bracket 106. At the top, an upward extension 109 is enlarged in interior diameter over that of chute 107, leaving annular shoulder 110 on which rests the lower rim of cup magazine 111; as here shown, a glass tube with closed top as seen in Fig. 3.

Just below annular shoulder 110 are recesses 112 in the walls of chute 107, diametrically opposite at left and right. The front of casing 105 has a compartment closed by a removable front plate 113; and shafts 114 are journaled in the casing to extend forward into this compartment and back into the respective recesses 112. In the recess each shaft has fixed on it a two-toothed pawl, and in the compartment each shaft has fixed on it a pinion segment 115. A rack frame 116 slides transversely, horizontally, in the compartment, between lower guides 117 and upper guides 118 and 119; comprising a lower main bar part which extends to the left through a notch in the compartment wall, considerably past said wall, ending in a knob 119. An upward projection 116' on this bar part has projecting to the left the upper rack 120 meshing downwardly with left pinion segment 115. The left end of this rack, engaging the compartment wall, limits left hand sliding of the frame 116. Left upper guide 118 bears on the top of the rack 120, and right upper guide 119 projects down to bear on top of the main bar part. This main bar part ends at the right in the right lower rack 121 meshing upwardly with right hand pinion segment 115. A spring 122 compressed between frame upward projection 116' and right upper guide 119 yieldingly holds the frame in its left position. An abutment 123 projects to the right from upward projection 116' over spring 122, keeping the spring in shape, and engages right hand upper guide 119 to limit right hand sliding of the frame 116. The front plate 113 holds the frame and spring against lateral displacement. The pawl teeth are so extended and proportioned, and the segments 115 are so meshed with the racks 120 and 121 that when lower pawl teeth 124 are projected into chute 107, upper pawl teeth 125 are swung into the respective recess 112, and vice versa. In this way, upper teeth 125 will move out into chute 107 under rim k of a next upper cup as lower teeth move in from under rim k of the lowest cup. This allows the lowest cup, as cup K' in Fig. 9, to fall to the position on carrier 65 had by cup K'' there shown; while next upper cup K''' with its rim caught as just explained is temporarily held up by upper teeth 125, to fall until its rim k engages outgoing lower teeth 124 when upper teeth 125 are drawn in away from the rim on return of rack frame 116 to the left from the right hand position taken for releasing lowermost cup K'.

The operating mechanism mounted on shelf 37 comprises a shaft 126, as best seen in Fig. 4, journaled in bearings 127 upstanding from the shelf; the rear end of this shaft connecting by a suitable coupling 128 with the stub shaft of a speed reducer 129 geared to the shaft of the motor 36 mounted on a bracket 130 extending to the right from the rear end part of the shelf 37. Shaft 126 extends forward from front bearing 127 and has fixed on it a small contact drum 131 of in-

sulating material covered, for half its circumference, by conducting segment 132. A pair of tongues 133 are mounted on a forward projection 134 of the bearing support, by screws 135 connecting wires 136 and 137 with the respective tongues, which are of resilient conductive material and spring up against the bottom of the drum 131. Just to the rear of front bearing 127 the cup-carrier-operating cam 138 is fixed on the shaft. Shortly back from that cam, the cup-release cam 139 is fixed on the shaft. Just back of this cam 139 the gate-operating cam 140 is fixed on the shaft. Just forward from the rear bearing 127 the faucet-operating cam 141 is fixed on the shaft. These may be seen more clearly in Fig. 5. The shaft 126 is rotated over to the left, as indicated by the arrow in Fig. 5; and in all views is stopped at the position it has between operations of dispensing.

In this position, contact tongues 133 bear up on the insulating portion of drum 131 close to the trailing end of conducting segment 132. Carrier-operating cam 138 has half its periphery concentric with the shaft, and the other half ascending sharply in a curve slightly convex to an approximately half circle symmetrical with the concentric part and then descending sharply in an opposite like slightly convex curve to the concentric part. In starting position, it depends its maximum-radius end from the shaft, to the left about 10 degrees from the vertical. Cup-release cam 139 is of shape similar to that of the just described carrier-operating cam, but its maximum-radius portion instead of being nearly semi-circular follows a curve concentric with the shaft for about 35 degrees. In starting position it is projected up substantially diametrically opposite to the dependence of the carrier-operating cam 138. The gate-operating cam 140 has half its periphery concentric with the shaft and the other half substantially conforming to a curve volute to the shaft. In starting position, the concentric half is down to the left about 10 degrees from the vertical like the maximum radius of cam 138 and the minimum radius of cam 139. The volute portion ascends around to the right, above the shaft to a substantially radial drop back to the concentric part; this drop inclining down to the right about 10 degrees below horizontal with the cam in its starting position. The faucet-operating cam 141 has about 90 degrees of its periphery concentric with the shaft, the other half conforming to inverse meeting volute curves and being symmetrical to the concentric part, i. e., each curve being about 135 degrees in extent. In starting position of the cam, least-radius part is symmetrical to a right downward incline of 45 degrees; the maximum-radius point being to the left up about 45 degrees. The right upper half of the periphery is followed in curvature by the radially inner edge of an opposing segment 142 unitary with the main part of the cam by an arm 143 spaced away from the cam and segment edges where it joins these parts.

The cup-carrier-operating lever 144, the cup-release lever 145, the gate-operating lever 146, and the faucet-operating lever 147 all are at the right of the respective cams 138, 139, 140 and 141 which actuate them, and all are fulcrumed on a front-to-rear fulcrum pin 148 fixed through the supports of the bearings 127 down close to shelf 37. Collars 149 fixed on pin 148 hold the levers to their positions along the pin. The levers 144 and 146 extend below shelf 37, which has its edge recessed for their accommodation.

The cup-carrier lever 144, the carrier 65 being at rear position, depends substantially vertically as shown, to the fork of short cup-carrier lever arm 77 where it has a stud 150 engaging in the arm fork. At this position the upper end part of this lever 144 is bearing on cam 138 at the beginning of ascent of the cam periphery. The cup-release lever 145 has its upper end enlarged and flat for attachment of an upstanding finger 151 that operates the successive-operation device 18 as later will be explained. This upper end engages the knob 119 of the cup-release rack frame; and it engages cam 139 at the start of its concentric portion. The gate-operating lever 146 depends somewhat slantingly to the left, ending in a fork that straddles a stud 152 on a block 153 embracing the left end part of door-operating rod 84, which is threaded and receives nuts 154 at opposite ends of the block 153, gripping it on the rod and allowing adjustment along the rod. The upper end of this lever 146 is a nose at the verge of the abrupt drop of the cam 140, holding the gate closed. The faucet-operating lever 147 swings at the rear of its cam 141 and has a roller 155 journaled on a stud in its front side, which roller has flanges straddling the main part of cam 141 as well as the segment 142 of this cam when it meets the roller. This lever 147 extends considerably above the cam 141, and a tension spring 156 hooks to its upper end and to the left cabinet wall 3. Shortly below this spring connection a stud extends forward from the lever and carries pivotally a left forward extending arm 157 that in turn has pivoted on its front end part a small yoke 158 that can swing in a transverse plane. A connecting rod 159 extends through this yoke and is threaded, receiving nuts 160 at the ends of the yoke to clamp the latter to the rod and allow adjustment along the rod. This rod 159 is bent forward, then backward, to pass around the cup-supply device, and has a terminal further backwardly bent part that extends through the top eye of a pin 161 turning in the faucet-plug arm-hub 47', down in which it is held by a nut 161' below the hub, on the pin. A flange 159' on the rod engages the front side of the pin eye, and a pin 159'' through the rod engages the rear side thereof. With the faucet closed, the roller 155 of lever 147 is at the beginning of the concentric part of the cam 141, with the cam segment 142 engaging its right end part to the right of the lever roller 155, holding the faucet positively closed. The arm 157 and yoke 158 are omitted in Fig. 5 and the rod 159 is connected directly to the lever 147, merely for simplicity of illustration; though of course this connection would be operative, loosely.

The coin-control devices, as before stated, are not of my invention, and so are illustrated in Fig. 10 in an arbitrary manner which may be roughly representative of the devices actually used or other such devices that may be used for the same purposes. The coin chute of device 17 is indicated at the right with a coin N rolling down it and about to make electrical connection between two contact members 162. The motor 36 that drives the operating mechanism is shown merely with the shaft 126 of the mechanism and the cup-release cam 139 thereon, as well as the contact drum 131 with its segment 132 and the two contact tongues 133. To represent the successive-operation device 18 a solenoid 163 has a vertically movable armature 164 yieldingly held up by a spring 165 and carrying on its lower end an extension below the solenoid coils on which

extension swings a pawl 166 with an upper arm 167 bearing on a pin 168. Below this assembly is a ratchet wheel 169 fixed on a shaft 170 extending back and having around it a spring 171 so connected to the shaft and so bearing on a pin in a fractional conductive ring 172 to the rear, around shaft 170 and concentric with the shaft, that the spring 171 tends to turn the shaft and wheel 169 over to the right as seen by the rear arrow. The descending pawl 166 will swing to the wheel 169 due to the action of its upper arm 167 at pin 168; the teeth of the wheel 169 being so raked that the pawl thus will turn the wheel and shaft over to the left, winding up spring 171. Within fractional ring 172, shaft 170 carries a contact member 173 seen occupying the gap in ring 172 when no current is passing in solenoid 163. The member 173 has a hub on which bears a contact blade 174. An escapement pawl is pivoted down at the right of wheel 169, with a left tooth 175 seen engaged with a wheel tooth under force of a spring 176 stretched from the opposite or right arm of the pawl to a fixed pin 177. At its middle, the escapement pawl has a depending arm 178 in the path of the tip 179 of the finger 151 before mentioned as being on the upper end of the cup-release lever 145 shown bearing on cam 139. As the maximum-radius part of cam 139 swings lever 145 to the right, the tip 179, engaging escapement pawl arm 178 will swing this pawl to disengage its lower left tooth from the wheel 169 and engage its upper right tooth 180 with the next approaching wheel tooth as the spring 171 turns the wheel over to right upon release by lower left tooth 175 of the escapement pawl.

Thus, if solenoid 163 has turned wheel 169 one tooth over to left, member 173 has moved to right into contact with fractional ring 172; but finger 151 would allow a one-tooth reverse turn, again bringing member 173 into the gap of ring 172. If a plurality of coins N rolled over the contact members 162, each time energizing solenoid 163, wheel 169 and therewith the contact member 173 will be turned over to the left as many teeth as there were coins N passing and contacting chute members 162, advancing member 173 a proportionate distance around fractional ring 172. As lever finger 151 acts but once, near the end, of each filled-cup delivery operation, to actuate the escapement pawl and allow spring 171 to return member 173 toward the ring gap, as many filled cups will be delivered as there were coins N deposited to contact chute members 162.

The leads 181 and 182 represent the connection S, Fig. 3, to a current source, as usual house wiring. Lead 181 is connected by wire 183 to one terminal of motor 36 that drives the operating mechanism. Lead 182 is connected by wire 184 to fractional contact ring 172, and also, by wire 136, to one tongue 133 that bears on drum 131. The other terminal of motor 36 is connected by wire 185 to the blade 174 that contacts the hub of rotatable contact member 173, and also, by wire 137, to the other tongue 133 that bears on drum 131. One chute contact member 162 is connected by wire 186 to lead 181; the other one of these members 162 is connected by wire 187 to one terminal of the coil of solenoid 163; the other terminal of this coil being connected by wire 188 to the other lead 182. It will be noted that the operating cams have to rotate nearly 100 degrees after lever finger 151 actuates the escapement pawl relative to ratchet

wheel 169; so that in the one operation, if there is only one, or the last operation of a plurality, member 173 will reach the gap in ring 172 when the about 100 degrees of this only or last rotation of the operating cams is to occur. It is for this reason that drum 131 with its segment 132 and tongues 133 bearing thereon are provided; the segment 132 maintaining the circuit after the member 173 reaches the ring gap, and breaking the circuit only after the segment 132 has passed from tongues 133. This segment 132 may be accurately located to cause the break in circuit just as the operating cams have completed their several operations.

Fig. 5 shows the general arrangement of the cams, but the diagram of Fig. 6 more accurately indicates the relative positioning or timing of the four operating cams on shaft 126; the lettering of Fig. 6 also being applied in the legends indicating the functioning of the cams, in Fig. 5. Angle A in Fig. 6, about 10 degrees, is that of abrupt gate-opening drop on cam 140; angle B, about 80 degrees, is that of forward movement of carrier 65 by cam 138; angle C, about 135 degrees, is that of opening the faucet 44 by the part of the cam 141 opposite its segment 142; and angle D, about 135 degrees, is that of closing of the faucet 44 by this segment 142. Angle b, about 90 degrees, is that of backward movement of the carrier 65 by cam 138; and angle d, about 180 degrees, is that of closing of gate 81 by the volute part of cam 140. Angle E, about 80 degrees, is that of release of cup K' to drop to carrier 65, by cam 139, and also of finger 151 that operates the escapement pawl of device 17; angle e, about 35 degrees, is that of dwell on cam 139 while the cup K' drops; and angle E', about 65 degrees, is that of return of the pawls of the cup-supply device, withdrawing their upper teeth 125 from under rim k of next upper cup K''' and projecting their lower teeth 124 to catch this rim and hold this next cup. Counter 189 acting to register the number of cups of liquid dispensed, is mounted on an upstanding bracket 189' on the rear left part of cup-dispenser bracket 106, actuated by faucet-operating lever 141 engaging rod 189'' of the counter mechanism.

Summarizing, with cup carrier 65 back with cup K'' on it, dropped as part of the last previous dispensing operation, gate 81 is closed, guard 101 is under spout 46, and gripper 93 is drawn into its boss 60. Cup K' hangs in chute 107. Deposited coin N connects members 162, energizing solenoid 163 to rotate ring 173 a distance of one tooth of wheel 169, starting motor 36 to rotate shaft 126 with the four cams thereon. Gate 81 quickly opens as the abrupt drop of cam 141 permits spring 85 to act, and carrier 65 moves forward, pusher 70 pushing cup K'' to position as cup K on casing bottom 56; the faucet is opened by cam 141, and in opening, its cam 50 permits guard wing 101 to swing from under the faucet spout by action of spring 103, and forces gripper 93 against cup K and the cup against opposite fixed gripper 89. The smaller end of faucet-operating cam 141 is so nearly concentric with shaft 126 that there is practically a dwell of open faucet 60 degrees of cam rotation, upon which increasingly rapid closure of the faucet occurs, by action of cam segment 142, aided by spring 156. In the last stage of faucet closure, faucet-plug-cam nose 54 returns guard wing 101 under the faucet spout; and spring 99 withdraws gripper 93 from cup K, as permitted by arm part

98 riding off of cam part 52. The gate 81 is being closed by volute of cam 140 while the faucet is opening and closing; and the carrier 65 has started back sufficiently earlier than beginning of gate closing to have pusher 70 back of the gate path as the gate begins to close; as compare angles *a* and *b* in Fig. 6. At completion of the carrier backward travel, the cup-supply device is operated, by cam 139 and spring 122 in the device, to drop a cup onto carrier 65, there to remain ready for the next dispensing operation of the machine. If a succession of coins C has been deposited, an equal number of dispensing operations, each of the cycle just described, will occur in immediate succession, by the means before fully described.

This provision for repeated operations is useful when a number of persons come in a group, for which each may deposit a coin or one may deposit coins for all; or any waiting persons may deposit their coins, not waiting until preceding persons have been served. The gripping by grippers 93 and 89 prevents a customer from unwittingly taking the cup K while liquid still is flowing from the faucet; which would result in excessive spillage on casing bottom 56, and of course give the customer less than full measure. The guard wing 101 prevents persons inserting paper or the like into the spout, as children tampering. Flange 86' hides wing 101 and discourages tampering with it. A tamperer is not apt to insert a finger into spout 46 while guard wing 101 is away therefrom, as the liquid then is flowing into a cup K, practically obstructing access to the spout. Even should the wing 101 close on an inserted finger, the rise of cam nose 54 is so abrupt that the obstructing finger has a great advantage over the power drive, and simply would stop the operation until the finger is withdrawn. It will be noted that wing 101 and gate 81 both are held closed positively by the respective cams 50 and 140; being spring-opened only when the cams release them. This effectively discourages tampering with the spout and with the interior parts and the waiting cup K' back of gate 81. Wing 101 also practically excludes dust from spout 46 in intervals between operations.

The machine has the advantage of showing operation, by presenting a cup, immediately after a coin is deposited; whereas with prior machines, so far as I am aware, the customer sees nothing presented until the cup has been filled and advanced. Also the display is somewhat enhanced to the customer seeing the liquid flowing into the cup.

It will be understood that modifications may occur, and it will be understood that though I have set forth my invention in specific detail, I am not limited to such precise disclosure.

What I claim as my invention and desire to secure by Letters Patent is:

1. In a machine of the character described, which comprises a liquid-supply device, a cup-supply device, a cup carrier reciprocatable to receive a cup from said cup-supply device and place the cup in receiving relation to said liquid-supply device, and mechanisms operative, respectively, to reciprocate said carrier, to start and stop the flow of liquid, and to cause cup-placing operation of said cup-supply device, in which machine the cup in its receiving relation is accessible to be taken manually, said machine including a gate movable alternately to close the path of the carried cup and to open said path, and mechanism operative to move said gate to open said path for

5 cup-placing operation of the carrier and to close said path after the cup has been carried in cup-placing direction past the place of closing.

2. A machine as set forth in claim 1, in which there is mechanism preventing manual taking of the cup until the flow of liquid has been substantially stopped.

10 3. A machine as set forth in claim 1, in which there is mechanism preventing access to the liquid-flow outlet in each interim between stopping and starting of the flow.

15 4. A machine as set forth in claim 1, in which there is mechanism for gripping the cup in said position before the flow has been substantially started, and for ungripping the cup for manual taking thereof when the flow has been substantially stopped.

20 5. A machine as set forth in claim 1, in which the liquid-supply device includes a faucet comprising a member movable by the respective mechanism alternately to allow and to stop the flow, said faucet having its outlet opening over the manually accessible place where the cup is taken, and said machine including a guard movable across and away from said outlet opening, and means moved incident to movement of the faucet member allowing the flow, to move said guard away from said outlet opening, and moved incident to movement of said faucet member for stopping the flow, to move said guard across said opening.

25 6. A machine as set forth in claim 1, in which the liquid-supply device includes a faucet comprising a member movable by the respective mechanism alternately to permit and to stop the flow, and in which is included gripping means having alternate movements to grip and ungrasp the cup in its flow-receiving position where the cup is accessible for taking, and means moved incident to movement of the faucet member for allowing flow to cause gripping movement of said gripper, and moved incident to movement of the faucet member for stopping the flow, to cause ungrasping movement of the gripper.

30 7. A machine as set forth in claim 1, said gate-moving mechanism mentioned therein including a cam and a lever operatively related to said cam and to the gate, said cam having a part so related to the gate as to be gradually active to close the gate and to hold the gate closed when the cam ceases operation, and having a part so related to the gate as to be successively active abruptly to permit opening of the gate, said machine including means to open the gate, said cam being so related, in time of action, to the time of action of the carrier-reciprocating mechanism that said gate is moved to open said path and close said path at the appropriate times as therein set forth.

35 8. A machine as set forth in claim 1, in which the mechanism operative to start and stop flow of the liquid includes a faucet comprising a member movable alternately to allow and to stop flow, and includes a cam and a lever operatively related to said cam and to said faucet member, said cam having a part active to cause opening movement of the faucet member and a part successively active to cause closing movement of said faucet member, said cam being so related, in time of action, to the time of action of the carrier-reciprocating mechanism that said faucet member is moved to allow flow of liquid when the cup has been carried substantially into its liquid-receiving relation to the faucet.
